UNITED STATES PATENT OFFICE.

JOHN H. HOOBER, OF KENTLAND, INDIANA.

CULTIVATOR.

SPECIFICATION forming part of Letters Patent No. 279,245, dated June 12, 1883.

Application filed November 13, 1882. (No model.)

To all whom it may concern:

Be it known that I, JOHN H. HOOBER, of Kentland, in the county of Newton and State of Indiana, have invented a new and useful 5 Improvement in Cultivators, which improvement is fully set forth in the following specification and accompanying drawings, in which—

Figure 1 is a side view of my improved adjustable wheel-cultivator. Fig. 2 is a top or plan view of same, and Fig. 3 is a rear view of portion of same.

The object of my invention is to provide an improved adjustable wheel-cultivator; and it 15 consists in the combination and arrangement of the various parts, as will be now set forth in detail.

In the accompanying drawings, A represents the wheels, secured to the axle B in the 20 ordinary manner. The axle B has an arch, B', centrally, to which is attached the hounds C, and to these hounds the tongue or pole is attached. To the under side of the hounds, forward of the arched axle, is a downwardly-projecting bracket or arm, C', having at its lower 25 end a pin or bolt, D. Stay-rods E', from the axle B to the hounds C, and clips D' hold the hounds rigidly to the axle.

F represents the cultivator-beam, provided 30 at its forward end with a metallic extension, E, provided with a slot, E'. The cross-pin D in the bracket or arm C' is designed to play in this slot. Midway the beam is provided with one or more hooks, G, which project upwardly and forward, and in such position relatively with the arch B' that when the beam is drawn backward so that the bolt D is at the 35 forward end of the slot E', as shown in Fig. 1, the hooks G will clear the arch B' when the 40 rear end of the beam is raised.

The rear end of the beam F is provided with a cross-bar, H, having a longitudinal slot, H', therein. A clip, I, passes around the beam, and has its limbs projecting up through the 45 slots H'. Nuts I' hold the bar H firmly to the beam, while the slot permits the bar to be moved laterally a limited distance. The ends J of this bar are turned up at right angles, and are provided with a series of holes to receive bolts J', which bolts also pass through the handles K, as shown. It will thus be observed that the handles are capable of being

adjusted vertically or laterally to suit the operator.

The arms which carry the shovels or cultivator-teeth are of peculiar construction and arrangement.

L represents one of the primary arms, hinged at its upper end to the side of the beam F, at a point directly behind the arch B'. The arm 60 from its hinged end curves outward and downward and rearward to within a limited distance of the ground, where it is bent so as to assume a horizontal position, as shown at L'. The horizontal extension projects rearwardly 65 a short distance, and then branches outward abruptly, and downward, with its lower end curved forwardly, as shown at M. The lower end of this arm is equipped with a cutter or blade, M', bolted thereto, as shown, by bolt N, 70 at a point somewhat to the rear of the center of said blade.

Extending from near the forward end of the blade M' to the curve M of the arm L is a brace, O. The lower end is provided, preferably, with a series of holes to receive the securing-bolt O'. The upper end of the brace has a slot, P, to receive the bolt P'. By this means the blade M' may be adjusted to any suitable angle.

On the inner side of the horizontal part L' of the arm L is a cleat, Q, with its opposite ends secured to the arm in such a manner as to permit the cross-arm R to pass down in the space thus formed between the cleat and arm. 85

Near the rear end of the beam F, on the upper side, is a plate, S, having four holes so located that the spaces between the holes are equal to the thickness or width of the beam. Two loops or clips, T—one on each side of the 90 beam—are secured to this plate S by nuts S'. The loops project down below the lower surface of the beam. A trough, U, is placed transversely across in these loops to receive the ends of the secondary cultivator-arms R. 95 The upper end of the secondary arm R rests in the loops T horizontally, and projects out therefrom a short distance, and is then bent downwardly to assume a vertical direction, inclining slightly forward, passing through 100 the space formed between the cleat Q and arm L, where it is firmly bolted to the arm L by the bolt V. The lower end of the arm R is equipped with a blade, M', and brace O,

similar to the arm L, heretofore described. The arms R, by means of the clips or loops T, are secured to the beam F adjustably, enabling the operator to bring the cultivator 5 teeth or blades on the opposite sides of the beam nearer together or farther apart, as described. The meeting-point of the two arms L R is also adjustable, as will be readily observed.

10 It is obvious that any form of teeth may be attached to the arms L R other than herein shown. When the truck is not needed for use and it is desired to dispense with it or use it for other purposes, the bolt D is removed and 15 the beam disengaged. In this event the team may be attached directly to the front end of the beam F.

What I claim as new is—

1. The truck having the arched axle B', and hounds C, having the brackets C' and bolt D, 20 in combination with the cultivator-beam having the looped forward end, and hooks G, substantially as herein set forth.

2. In cultivators, the combination of the beam having the rear transverse slotted bar, H, 25 with the upturned ends and the handles K, and the clips T with the crossed arms L R, substantially as herein set forth.

In testimony that I claim the foregoing I have hereunto set my hand, this 3d day of November, 1882, in the presence of witnesses.

JOHN H. HOOBER.
